BRUSH ASSEMBLY FOR VACUUM CLEANERS
AND THE LIKERudolph Hemrich, Detroit, Mich., assignor to
Eureka Vacuum Cleaner Company, Detroit,
Mich., a corporation of Michigan

Application June 8, 1936, Serial No. 84,213

2 Claims. (Cl. 308—20)

This invention relates generally to sweepers or vacuum cleaners and refers more particularly to an improved brush mounting for cleaners of the above type.

In vacuum cleaners, it has been customary to provide bearings for the opposite ends of the brush having the dual function of journalling the brush in the nozzle of the cleaner housing and retaining the brush in assembled relation with the housing. Although this general arrangement has been in commercial use for some time, nevertheless it has one serious objection, in that the bearings are not fixed to the brush with the consequence that when the brush is removed from the housing for cleaning or other purposes, the bearings slip off the ends of the brush requiring them to be re-assembled with the brush and manually held in place while the brush is being attached in the nozzle of the cleaner housing.

One of the principal objects of this invention is to overcome the foregoing objections without appreciably increasing the cost of manufacture and to accomplish this result by a construction rendering it possible to employ a quick, detachable connection between the brush and cleaner housing.

In accordance with this invention, the bearings while separate from the brush are connected to the latter in such a manner as to form an assembly capable of being removed from and assembled with the cleaner housing as a unit.

The foregoing, as well as other objects, will be made more apparent as this description proceeds, especially when considered in connection with the accompanying drawing, wherein:

Figure 1 is a side elevational view of a vacuum cleaner equipped with a brush mounting constructed in accordance with this invention, and having certain parts broken away for the sake of clearness;

Figure 2 is a fragmentary bottom plan view of the construction shown in Figure 1;

Figure 3 is an enlarged elevational view of the brush having certain parts broken away for the sake of clearness; and

Figure 4 is a sectional view taken substantially on the plane indicated by the line 4—4 of Figure 3.

For the purpose of illustration, I have shown my improved brush mounting in association with a vacuum cleaner of the portable type comprising essentially a housing 10 for the suction creating mechanism and a brush 11 rotatably supported in the nozzle 12 of the housing. In the present instance, the brush 11 is driven by the

prime mover (not shown) of the suction mechanism by means of a belt 13 reeved around an enlarged portion 14 on the brush intermediate the ends of the latter and around the drive pulley (not shown) of the prime mover.

In the specific embodiment of the invention selected herein for the purpose of illustration, the brush comprises a cylindrical wood roll 15 permanently secured within a metal tube 16 and having axially lined shafts 18 anchored in opposite ends thereof. The shafts 18 extend beyond the opposite ends of the roll 15 and are journalled in bearings 19 having axially extending portions 20 adapted to be snapped into engagement with suitable clips 21 secured within the nozzle 12 at opposite ends of the latter. The arrangement is such as to permit the brush and the bearings, therefor, to be readily assembled with and removed from the nozzle. In this connection, it is to be noted that the nozzle is equipped with a removable guard 22 and this guard also has a snap engagement with the housing to permit the same to be readily detached when it is desired to remove the brush assembly.

Referring now more in detail to the bearings, it will be noted from Figure 3 that the hub portions 20 are substantially tubular in cross section and are closed at the outer ends thereof by means of the integral end walls 23. The inner ends of the tubular portions 20 of the bearings 19 are provided with radially outwardly extending flanges 24 terminating in annular inwardly extending flanges 25 adapted to overlap the extremities of the tubular casing 16 of the brush. The flanges 25 are free from contact with the casing 16 so as not to interfere with rotation of the brush relative to the bearings, and felt or other suitable non-metallic washers 26 are interposed between the ends of the roll 15 and the adjacent surfaces of the radial flanges 24 on the hubs to minimize any sound that may be produced by axial shifting movement of the brush relative to the bearings.

The free ends of the shafts 18 extend axially into the hub portions 20 of the bearings and are journalled in wooden bearing members 27 having a forced fit in the hub portions 20. Each of the bearing members 27 comprises two sections 28 and 29 secured in the hub portions 20 in axial juxtaposition. Both sections are provided with axially extending bores 30 therethrough for receiving the extremities of the shafts 18 and the outer sections 29 are secured in the hub portions 20 against the end walls 23 thereof. The inner sections 28, on the other hand, extend

inwardly beyond the radial flanges 24 on the hub and project into enlarged recesses 31 formed in the ends of the roll 15. The arrangement is such as to provide an extended bearing engagement 5 with the shafts 18 and, at the same time, permit the use of a brush of maximum length. Attention is called to the fact at this time that suitable fibre washers 32 are positioned between the inner ends of the bearing sections 28 and the 10 adjacent wall of the recess in the roll 15. The washers 32 cooperate with the washers 26, previously described, in reducing the noise of operation of the roll and, at the same time, minimizes the wear between the two relatively rotatable 15 surfaces.

It has previously been stated that the present invention contemplates a brush construction wherein the bearings are attached to the brush proper in such a manner as to be retained in assembled relation with the brush when the latter is removed from the nozzle. This is accomplished in the present instance by recessing the outer surfaces of the sections 28 of the bearing members 27 in the manner designated by the reference 25 character 33 in Figure 3. The recesses 33 co-operate with the adjacent surfaces of the outer sections 29 of the bearing members to retain spring washers 34 split as at 35 and adapted to receive the reduced portions 36 of the shafts 18. 30 The normal internal diameter of the washers 34 is sufficiently greater than the diameter of the reduced portions 36 of the shafts 18 to permit free rotation of the shafts, but is less than the external diameter of the portions of the shafts 35 proper on opposite sides of the reduced portions 36 in order to prevent the bearings 19 from slipping off of the shafts 18 when the brush is removed from the casing.

Assembly of the bearings 19 with the ends of 40 the brush 11 is permitted by reason of the fact that the extremities of the shafts 18 are tapered, as at 37, to provide for spreading the washers 34 sufficiently to permit the end portions of the shafts 18 beyond reduced portions 36 thereof, to 45 be extended through the washers into the outer sections 29 of the bearing members 27. It will, of course, be understood that the degree of spreading of the washers required for assembly is within the elastic limits of the washers and, 50 accordingly, the latter will assume their normal positions as soon as the reduced portions 36 of the shafts 18 assume positions within the open-

ings through the washers. Upon reference to Figure 3, it will be noted that the axially spaced shoulders 38 formed by the reduced portions 36 of the shafts 18, are also tapered slightly to permit forcibly detaching the bearings from the ends 5 of the brush.

Thus, from the foregoing, it will be observed that I have provided a relatively simple and inexpensive brush construction having provision for retaining the bearings in assembled relation therewith when removed from the cleaner. It will also be noted that my improved construction permits the bearings to be readily assembled with the brush and, in addition, provides for forcibly detaching the bearings from the brush 10 when necessary. 15

What I claim as my invention is:

1. A bearing and shaft assembly, comprising a shaft having a reduced portion, a bearing having an axially extending bore therein for rotatably receiving the shaft and having an annular recess surrounding the reduced portion of the shaft, and means retained in the annular recess in the bearing and surrounding the reduced portion of the shaft for retaining the bearing in assembled relation with the shaft, said means including a split washer having an internal diameter less than the maximum diameter of the shaft and greater than the diameter of the reduced portion of the shaft. 20 25

2. A bearing and shaft assembly, comprising a shaft having a reduced portion intermediate the ends thereof, a bearing having an axially extending bore therein for rotatably receiving the shaft and having an annular recess surrounding the reduced portion of the shaft, and a split spring washer retained in the annular recess in the bearing and having an internal diameter exceeding the diameter of the reduced portion of the shaft but smaller than the diameter of the portions of the shaft on opposite sides of the reduced portion, said washer effective upon relative axial movement of the bearing and shaft toward each other to spread sufficiently to permit the reduced portion of the shaft to be positioned within the opening of the washer and also effective upon relative movement of the shaft and bearing in directions away from each other to spread sufficiently to permit the bearing to be removed from the shaft. 40 45 50
